ELECTRIC SWITCH

Robert W. Bachi, Marion, Ind., assignor, by mesne assignments, to Controls Company of America, Schiller Park, Ill., a corporation of Delaware

Application July 21, 1955, Serial No. 523,521

9 Claims. (Cl. 200—6)

This invention relates to electric switches and has more particular reference to improvements in single pole double throw electric switches.

It is the purpose of this invention to provide a single pole double throw electric switch of simplified construction featuring a floating contactor normally occupying a switch off position seated upon a pair of spaced supports which provide alternate fulcrums about which the contactor may be tilted to carry contact means thereon in opposite directions toward and from engagement with a pair of stationary contacts.

More specifically, this invention has as its purpose the provision of an electric switch of the character described, wherein the alternate fulcrums upon which the contactor is floatingly supported are carried by a pair of plunger like actuators which when alternately moved out of a normal switch off position, effect tilting of the contact portion of the contactor in opposite directions toward and from engagement with its cooperating stationary contact.

Still another purpose of this invention resides in the provision of an electric switch of the character described wherein a single spring acting upon the floating contactor at a point intermediate its alternate fulcrums yieldingly maintains the contactor seated on the fulcrums and also serves as biasing means for both actuators to yieldingly urge the actuators in the same direction.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates two complete examples of the physical embodiments of the invention constructed according to the best modes so far devised for the practical application of the principles thereof, and in which;

Figure 1 is an elevational view of a single pole double throw switch embodying the principles of this invention, portions thereof being broken away and shown in section;

Figure 2 is a view similar to Figure 1 but showing the contactor of the switch tilted out of neutral position to one circuit closing position;

Figure 3 is a view similar to Figure 2 but showing the contactor of the switch tilted to its other circuit closing position; and

Figure 4 is a view similar to Figure 1 showing a modified embodiment of the invention.

Referring now more particularly to the accompanying drawing in which like numerals designate like parts, the numeral 5 generally designates a supporting structure or housing for the switch having a base 6, a top wall 7 spaced a distance above the base, and upright end walls 8 and 9 extending between and joined to the base and the top wall.

2

The switch mechanism 10 of this invention is mounted in the housing and comprises an elongated contactor blade 11, a pair of vertically spaced stationary contacts 12 and 13 fixed on the end wall 9 of the housing, and a pair of actuators 14 and 15 movably carried by the base 6. The actuators have plunger-like lower end portions 16 which are slidably received in spaced vertical holes 17 in the base opening to its upper surface, and are further provided with enlargements 18 thereon spaced from their upper ends and positioned above the base 6.

The upper surfaces of the enlargements 18 are rounded and provide fulcrums upon which the contactor 11 seats. For this purpose, the contactor is provided with holes 20 to loosely receive the pilot-like upper end portions 21 of the actuators which project upwardly from the enlargements 18, and the pilot-like upper end portions of the actuators thus hold the contactor against edgewise displacement from the fulcrums provided by the enlargements 18 without interfering with alternate tilting motion of the contactor about its fulcrums.

In the embodiment of the invention illustrated in Figures 1 to 3, the switch is provided with an operating member 23 comprising a rod which is axially slidably received in a bore 24 in the base crosswise intersecting the holes 17 in which the lower plunger-like ends of the actuators slide. Normally the rounded lower ends of the actuators engage the periphery of the rod 23 as shown in Figure 1, to be held thereby in predetermined positions on the base with their enlargements 18 spaced equal distances from the upper surface of the base.

A coiled compression spring 26 exerts a downward force upon the contactor to yieldingly hold it engaged with both of its fulcrums, and this spring, acting through the contactor, also presses the actuators downwardly to assure engagement of their lower ends with the periphery of the rod 23. The spring 26 is properly held in place exerting its force upon the contactor at a location intermediate its fulcrums by a pilot 27 projecting downwardly into the coils of the spring from the top wall 7 of the supporting structure, and by a boss 28 on the upper face of the contactor blade 11 intermediate the enlargements 18 upon which the contactor rests.

In the normal positions of the actuators described, therefore, the enlargements 18 on the actuators hold the contactor 11 in a neutral position extending lengthwise over the base substantially parallel thereto but spaced therefrom, and with the outer end portion 30 of the contactor remote from its fulcrums substantially midway between the upper and lower stationary contacts 12 and 13 respectively.

The contactor 11 is tilted about one or the other of its fulcrums toward engagement with one or the other of the stationary contacts as a consequence of motion of one of the actuators out of its normal position defined by the engagement of its lower end with the periphery of the operating rod 23. For this purpose, the operating rod is provided with a circumferential groove 32 therein which may normally occupy a position substantially midway between the two actuators in the neutral or switch off position shown in Figure 1.

When the operating rod is shifted to the left to the position shown in Figure 2, its circumferential groove 32 aligns with the plunger-like lower end portion of the actuator 14, and the actuator 14 is propelled downwardly under the force of the compression spring 26 into the groove 32 while the actuator 15 remains in its normal position. As a consequence, the spring 26, which acts upon the contactor at an area intermediate its two fulcrums, causes the contactor to tilt upon the fulcrum of the actuator 15 in a counterclockwise direction to carry contact means on its outer end portion 30 up-

wardly into engagement with the upper stationary contact 12 as shown in Figure 2. It will be understood that the outer end portion 30 of the contact blade may itself provide the contact means on the contactor although it is the usual practice to secure a contact point 34 to the blade for this purpose.

While the contactor 11 may be made of relatively stiff metal, it is shown as a thin, flexible blade. Consequently, the engagement of its contact means 34 with the upper stationary contact 12 will cause the blade to flex and assume an upwardly bowed attitude (as shown in Figure 2) as a consequence of the spring force exerted on the contactor at the side of its fulcrum remote from the stationary contact 12.

When the operating rod 23 is shifted to the right from its neutral position seen in Figure 1 to bring its circumferential groove 32 into alignment with the actuator 15, the latter is propelled downwardly into the groove of the operating rod by spring 26 while the other actuator 14 remains in its normal position, and the contactor 11 is thus caused to tilt in a clockwise direction to carry the contact means on its outer end portion downwardly into engagement with the lower stationary contact 13 as seen in Figure 3. In this case, the contactor blade will assume a downwardly bowed attitude by reason of the fact that it is supported at its opposite end portions while the spring force is being applied to a middle portion thereof.

It will be understood, of course, that the stationary contacts 12 and 13 are so spaced that as the contactor is tilted to either circuit closing position, its contact means 34 will be engaged with one or the other of the stationary contacts before the depressed actuator bottoms in the groove 32 of the operating rod 23.

It will also be apparent that while the operating rod has been shown provided with but a single circumferential groove 32, there may be instances when it is desirable to provide the rod with more than one groove to enable selective depression of the actuators, or even simultaneous depression of the actuators, in which latter event the contact means 34 is brought into engagement with the lower stationary contact 13.

Terminals 35 connected with the stationary contacts 12 and 13 may be provided on the end wall 9 of the switch housing, and floating contactor 11 may be connected by a flexible pigtail 36 with a third terminal 37 on the end wall 8 of the housing. The point of connection between the flexible lead or pigtail 36 to the contactor 11 is preferably at some location intermediate the fulcrums on the actuators so that the lead does not have to be excessively long to compensate for the tilting motion of the contactor.

In the embodiment of the invention shown in Figure 4, the enlargements 18 on the actuators provide downwardly facing shoulders 39 on their undersides which are yieldingly held engaged with the upper surface of the base 6 by the spring 26 to define the normal positions of the actuators, and the neutral position of the contactor. In this case also, the lower plunger-like end portions 16 of the actuators project all the way through the base to have portions exposed at its underside to provide for manual depression of the actuators upwardly into the housing. No operating member such as the rod 23 previously described is necessary.

Thus when the actuators are alternately depressed in upward directions out of their normal positions, the contactor is caused to tilt in opposite directions upon the fulcrums provided by the rounded upper surfaces of the enlargements 18 on the actuators in a manner similar to that described previously.

From the foregoing description, taken together with the accompanying drawings, it will be readily apparent to those skilled in the art that this invention provides an exceptionally simple single pole double throw electric switch by reason of the novel manner in which the

contactor of the switch is floatingly supported on alternate fulcrums which effect tilting of the contactor in opposite directions when the fulcrums are alternately shifted out of normal positions.

What I claim as my invention is:

1. In an electric switch: a base; a contactor overlying the base in spaced relation thereto and having contact means at one portion thereof; a pair of actuators extending between the base and the contactor; means mounting said actuators in spaced, side by side relationship on the base and for motion to and from defined positions along paths which intersect the contactor; means on said actuators loosely engaged with portions of the contactor which are spaced in the same direction from said contact means to provide alternate fulcrums at one side of the contactor and engaged thereby, about either of which fulcrums the contactor may tilt; and spring means acting on said contactor in a direction to maintain the contactor seated upon both fulcrums; motion of one

10 of said actuators away from its defined position effecting tilting of the contactor about one of said fulcrums to carry the contact means on the contactor in one direction, and motion of the other of said actuators away from its defined position effecting tilting of the contactor about the other of said fulcrums to carry the contact means on the contactor in the opposite direction.

2. In an electric switch having a contactor, means mounting the contactor for back and forth tilting motion so as to carry contact means on the contactor in opposite

30 directions, comprising: a base having spaced substantially parallel holes therein; a pair of plunger-like actuators each having one end portion slidably received in one of said holes; cooperating means on the base and said actuators defining the normal position of each of said

35 actuators, out of which normal positions the actuators are movable independently on one another; means providing a fulcrum on each actuator spaced from but facing the other end thereof; said contactor seating upon said fulcrums and having holes therein to loosely receive the other end portions of the actuators which project from said fulcrums; and spring means acting upon the contactor in a direction to hold the contactor seated on both of said fulcrums; motion of one of said actuators away from its normal position effecting tilting of the contactor about one of said fulcrums to carry the contact means on the contactor in one direction, and motion of the other of said actuators away from its normal position effecting tilting of the contactor about the other of said fulcrums to carry the contact means on the contactor in the opposite direction.

3. In an electric switch: a supporting structure having a base; spaced stationary contacts on the supporting structure; a contactor overlying the base and having contact means on one portion thereof cooperable with said stationary contacts; a pair of actuators extending between the base and another portion of the contactor; means mounting said actuators on the base for back and forth motion along spaced paths which intersect the contactor; cooperating means on the actuators and the base defining the normal positions of the actuators; means on the actuators providing alternate fulcrums engaged with one side of the contactor and about either of which fulcrums the contactor may tilt; and spring means acting on said contactor in a direction to maintain the contactor seated upon both fulcrums so that the contactor is normally held thereby with its contact means between and spaced from said stationary contacts when both actuators are in their normal positions; motion of one of said actuators away from its normal position effecting tilting of the contactor about one of said fulcrums to carry said contact means in one direction into engagement with one of the stationary contacts, and motion of the other of said actuators away from its normal position effecting tilting

60 of the contactor about the other of said fulcrums to carry

65

the contactor about the other of said fulcrums to carry

70

75

said contact means in the opposite direction into engagement with the other stationary contact.

4. The electric switch set forth in claim 3 further characterized by the provision of cooperating loosely engaging means on the contactor and said actuators for holding the contactor against displacement from said fulcrums without interfering with tilting of the contactor thereon.

5. In an electric switch: a supporting structure having spaced stationary contacts mounted thereon and having a base provided with a pair of holes on spaced upright axes; a plunger axially slidably received in each of said holes and projecting upwardly from the base; cooperating means on the base and said plungers defining the normal axial positions of said plungers in their holes, out of which normal positions the plungers are movable axially and independently of one another; an enlargement on each plunger spaced from the upper end thereof but lying above said base, said enlargements providing spaced fulcrums having rounded upper surfaces; an elongated contactor having one portion seated upon said fulcrums and having holes therein through which the upper end portions of the plungers loosely project to hold the contactor against displacement from the fulcrums in directions normal to the plunger axes, without interfering with tilting motion of the contactor about either fulcrum, said contactor having contact means in another portion thereof remote from said first designated portion of the contactor which contact means is cooperable with said stationary contacts; and a spring carried by the supporting structure and acting upon a portion of the contactor intermediate said fulcrums and in a direction to hold the contactor engaged therewith so as to prevent accidental displacement of the contactor off of the upper end portions of the plungers in the direction of the plunger axes; motion of one of said plungers away from its normal position effecting tilting of the contactor about one of said fulcrums to carry said contact means in one direction toward engagement with one of the stationary contacts, and motion of the other of

said plungers away from its normal position effecting tilting of the contactor about the other of said fulcrums to carry said contact means in the opposite direction toward engagement with the other stationary contact.

5 6. The electric switch set forth in claim 5 further characterized by the provision of movable operating means connected with said plungers for effecting motion thereof out of their normal positions.

10 7. The electric switch set forth in claim 6 wherein said operating means comprises a bar carried by the base beneath the plungers and against which their lower ends bear to define the normal position of the plungers, said bar being constrained to back and forth sliding motion along a path crosswise of both plungers and being 15 notched to provide for movement of the plungers out of their normal positions by said spring as a consequence of sliding of the bar back and forth to positions at which the lower ends of the plungers align with the notched portion of the bar.

10 20 8. The electric switch set forth in claim 5 wherein the lower end portions of the plungers project through the base and are exposed at the exterior of the supporting structure to provide for manual actuation of the plungers out of their normal positions.

25 9. The switch set forth in claim 8 further characterized by the fact that said enlargements on the plungers define downwardly facing shoulders at their undersides which are yieldingly held engaged with the base by said spring to define the normal positions of the plungers.
